CLAIM

The ornamental design for a wine opener, as shown and described.

DESCRIPTION

FIG. 1 is a front elevation view of the claimed design; FIG. 2 is front elevation view thereof, at a reduced scale and in an alternate position

FIG. 3 is a top plan view thereof; and,

FIG. 4 is a side elevation view thereof, the opposite side elevation view being identical.

The broken line showing in FIGS. 1 and 2 is for illustrative purposes only and forms no part of the claimed design.
